US0D1025566S

(12) **United States Design Patent** (10) Patent No.: **US D1,025,566 S**
(45) Date of Patent: ** May 7, 2024

(54) SHOE	D205,026 S	6/1966	Rosenbaum et al.
(71) Applicant: NIKE, Inc. , Beaverton, OR (US)	3,965,516 A	6/1976	Romero et al.
(72) Inventors: Thomas Belhacene , Portland, OR (US); Earl Stewart , Portland, OR (US); Philip Woodman , Treviso (IT)	D243,642 S	3/1977	Voorhees
(73) Assignee: NIKE, Inc. , Beaverton, OR (US)	4,213,255 A	7/1980	Olberz et al.
(**) Term: 15 Years	D272,772 S	2/1984	Kohn
(21) Appl. No.: 29/894,917	D273,246 S	4/1984	Tonkel
(22) Filed: Jun. 15, 2023	4,617,745 A	10/1986	Batra
Related U.S. Application Data

(57) CLAIM

The ornamental design for a shoe, as shown and described.

DESCRIPTION

FIG. 1 is a bottom view of a shoe showing our new design;

FIG. 2 is a side view thereof; and,

FIG. 3 is an opposite side view thereof.

The washed-out lighter grey portions are for the purpose of illustrating portions of the shoe which form no part of the claimed design.

1 Claim, 3 Drawing Sheets
